CLASP

Julius Lenneberg, New York, N. Y.

Application November 3, 1949, Serial No. 5,850

Term of patent 14 years

(Cl. D45—4)

To all whom it may concern:

Be it known that I, Julius Lenneberg, a citizen of the United States of America, residing at New York, in the county of New York and State of New York, have invented a new, original, and ornamental Design for a Clasp, of which the following is a specification, reference being had to the accompanying drawing, forming part thereof.

In the drawing:

Fig. 1 is a perspective view of a clasp, embodying my new design; and

Fig. 2 is a perspective view thereof illustrating the clasp open.

I claim:

The ornamental design for a clasp, as shown.

JULIUS LENNEBERG,
